UNITED STATES PATENT OFFICE

CHARLES H. HUGHES, OF HACKENSACK, NEW JERSEY, ASSIGNOR, BY MESNE ASSIGNMENTS, TO SEMET-SOLVAY ENGINEERING CORPORATION, OF NEW YORK, N. Y., A CORPORATION OF NEW YORK

COKE OVEN

Application filed June 18, 1926, Serial No. 116,764, and in Canada June 19, 1925.

This invention relates to by-product coke ovens, particularly ovens of the horizontal flue type with regenerators individual to, and parallel with, each oven of the block or battery. In ovens of this character as constructed hitherto, it has been considered necessary, in order to maintain proper heat conditions in the floor of the oven, to interpose so-called sole flues directly beneath the floors of the several oven chambers, and to cause the entire body of the hot spent gas from the heating flues on their way to the regenerators, as well as the entire body of all of the air which had passed through the regenerators on their way to the heating flues, to travel through these sole flues in a direction parallel to the flow of gas through the heating flues and during such travel to give up heat to the floor of the oven. These sole flues thus form a heat abstracting connection between the heating flues located at the sides of the division walls of the oven chambers, and the regenerators in which the air was heated before it was mixed with fuel in the heating flues to support combustion. Heat taken up by the lateral walls of the sole flues was dissipated through the masonry and the only point of effective heat transfer in the sole flues was through the floor of the oven. Ovens of this character, although capable of producing a good quality of coke, were expensive with respect to structure and consumed excessive amounts of fuel.

The object of the present invention is to improve structures of the class indicated above in such a way as to cheapen the construction and greatly improve the economy of the process. Briefly summarized, the characteristic feature of the present invention will be found in the fact that the heat necessary to support the proper temperatures in the oven floor is abstracted, not from gases travelling through any sole flue, but from a gas space which is directly associated with and located in the interior of the upper part of the regenerators and which is in direct thermal communication with the underside of the floor of the oven, while the gas connection between the regenerators and the

heating flues for both the incoming air and the outgoing products of combustion is in each case a direct connection. By constructing the oven in this manner, i. e., by establishing a direct connection between the regenerators and the heating flues, and thus dispensing with and obviating the necessity for the customary sole flues, certain important advantages are obtained, as will be set forth in detail hereinafter.

According to this invention the incoming air from the regenerators of a by-product coke oven having horizontal zigzag heating flues in the heating walls thereof, regenerator sets beneath the oven, and means for reversing the gas flow through the respective regenerator sets and heating flues, is led directly and without first passing it through a sole flue into the air inlet ports of the flue system whilst the products of combustion from the flue system are led, without first passing them through a sole flue, into their regenerators, whereby, irrespective of the direction of flow of the gas or which set of regenerators is used as the preheating set, the gases entering and leaving the flue system will always travel in a direct path, free from sole flue conduits, into or out of the flue system and into and out of the associated regenerators. At the same time the proper thermal conditions are maintained in the floor of each oven by the heat which is transferred to the underside of said floor from gases accumulating in the upper part of the regenerator chambers.

A typical and satisfactory example of my present invention is illustrated by the accompanying drawings, in which Fig. 1 is a longitudinal section taken through one of the heating chambers of the oven, and in line 1—1 of Figs. 2 and 3; Fig. 2 is a cross-section on line 2—2 of Fig. 1; Fig. 3 is a cross-section one line 3—3 of Fig. 1, and Fig. 4 is a diagrammatic view showing the circulation system.

The oven illustrated operates with the well-known periodical reversal of flow, and embodies the usual adjuncts (valves, etc.) for effecting this reversal; these parts, being well known, have not been indicated in the

drawings. The block or battery of ovens comprises a series of parallel horizontal coking chambers A separated by upright division walls B at each side of which extend zigzag heating flues C of well-known character, the main portions of said flues being horizontal, the entire flue system being incorporated in a separate lining (shown cross-hatched in the drawings). Means (nozzles) for supplying fuel (gas) to the heating flues are indicated at D. A set of regenerators E', E², E³, E⁴ are located directly beneath each oven chamber, each of said regenerators being relatively narrow in width and deep in height. The roof of the set of regenerators is formed by the floor of the oven which is constructed of masonry supported by corbeling of like material as shown in Fig. 2 and which, as previously explained, is such that it will enable the heat from the regenerators to be transferred through the said oven floor to the charge in the interior of the oven under maintenance of proper thermal conditions in the oven floor. At the end of the lower horizontal member of each zigzag flue C it opens directly through port C' (without the interposition of any sole flue) into the regenerator E'. The upper horizontal member of each zigzag heating flue C is connected by a riser F' or F², located at the other end of the oven, with the regenerator port C² of regenerator E⁴. The risers F' lead from their respective regenerators E⁴ to the heating flues on two sides of one of the oven chambers, while the risers F² lead to the heating flues on the sides of the adjacent oven chambers. Thus, from each regenerator there are established connections leading to and from both of the two zigzag flue series on each side of the oven chamber.

It is to be noted that the connection between the regenerators and the heating flues is entirely a direct connection. By a direct connection I mean one which so connects the regenerators with the flue systems that all the effective heat given off by the entire flue systems connected with the ports of the respective regenerators is imparted wholly through those walls of the heating flue system C which are adjacent to the coking chambers A laterally of the coking material in the chambers A, and not in part through a sole flue, the necessary heat for the floor of the oven being transmitted from the upper open portion of the regenerators E', E², E³ and E⁴. This is in sharp contrast to the structural arrangement of older ovens such as shown, for instance, in my former Patent No. 1,055,536 of March 11, 1913, or the King Patent No. 970,720 of September 20, 1910, wherein between the wall flue systems and the regenerators proper the gases were always forced to travel through a special flue called the sole flue. This flue was

a channel formed in heavy masonry and positioned directly under the floor of the oven, and thus presented a refractory masonry barrier and a flue space between the checkerbrick of the regenerator and the floor of the coke oven. With this old construction the heat radiated upwardly from the checkerbrick of the regenerators was absorbed and largely dissipated in the masonry and thus was never able to participate effectively in the heating of the floor of the oven or the charge in the coking chamber. By my new construction not only were these defects of the prior structures remedied, but wholly new and valuable effects were obtained. In other words, when the entering air has acquired its maximum temperature in the regenerator, it does not thereafter have to give up a substantial part of its thus acquired heat to the walls of the sole flue, but passes directly and without diminution of the maximum heat acquired by it in passing through the regenerators, into the heating flue system and, vice versa, the hot products of combustion from the heating flue system pass directly into the regenerators, retaining the whole of their heat in so doing and without being compelled to give up an appreciable part of their heat to the walls of a sole flue beneath the oven chamber before entering the regenerators. The connections of the heating flues C and of the risers F', F² with the regenerators E⁴, are made near the outer upper corners of these regenerators and lower than the uppermost part of the gas space at the top of said regenerators and in opposed relation with respect to each other, so that the gases from the heating flues will enter the regenerators as diametrically opposed streams. These streams impinge against each other and coalesce into one body of gas which fills the entire upper portion and cross-section of the regenerator and then travels in a downward direction and thus utilizes all of the heat-receiving capacity of the regenerator. At the opposite corners (that is, the inner lower corners) these regenerators are connected with channels G', G² (formed by baffles S) respectively, the upper ends of which are in turn connected with the upper portions of inner regenerators E², E³ respectively, thus forming a sinuous sheet-like passage from the outer to the inner regenerators, or vice versa. The dimensions of this passage are somewhat larger than the aggregate dimensions of the ports or channels which connect the flues and the regenerators, but smaller than the aggregate dimensions of the air inlet (or gas outlet) ducts at the bottom of regenerators E² and E³. By this arrangement the flow of incoming air is gradually accelerated while the flow of the out-going products of combustion is gradually diminished. The bottom of regenerators E² and E³ have open-

ings which communicate with the upper portions of passages H^2 , H^3 respectively, said passages H^2 and H^3 extending transversely of the coking chambers, under the regenerators. By having the lower ends of the channels G' , G^2 connected with the regenerators E' , E^2 at the corners diagonally opposite to those at which said regenerators are connected with the heating flues C , I secure a proper and effective flow of the combustion gases or of the air through said regenerators.

The flow of the combustion gases from the heating flues to the regenerators (whether the flow takes place through the risers F' or F^2 , or through the direct connections C') always takes place so that the streams of gases impinge against each other and form a body of gas which completely fills the regenerator chamber and spreads over all of the checkerbricks in the regenerator.

The passages H^2 , H^3 communicate by openings J , J' with adjacent passageways H' , H^4 respectively, extending parallel to the passages H^2 , H^3 . One end of this system H' , H^2 , H^3 , H^4 has a stack connection controlled by dampers or other suitable means functioning as valves. Air inlets likewise controlled by dampers or valves are also provided in this system H' , H^2 , H^3 , H^4 at appropriate points. The aforesaid dampers or valves are indicated in Fig. 4 by the legend "valve". Alternative positions are indicated for each valve by the use of solid lines and dotted lines. The solid lines indicate the position of the various valves with respect to the conduits controlled by them when the gas and air flow is in one direction, whereas the dotted lines indicate the position of the valves when the gas and air flow is reversed.

During one period of operation, the dampers are so adjusted (this being the position shown in Fig. 4) that air will enter, as indicated by the full arrows shown in Fig. 4, the passages H^2 , J , H' and pass upwardly through the inner regenerators E^2 , downwardly in the channels G' , upwardly through the outer regenerators E' , the air thus heated by contact with the hot checkerbrick of the regenerators E^2 , E' being conveyed directly to lower ends of the zigzag heating flues C . In these flues, combustion takes place, and the resulting gases pass from the upper ends of the flues C downwardly through the risers F' , F^2 to the upper portions of the outer regenerators E^4 . The hot gases, as indicated by the full arrows shown in Fig. 4, traverse these regenerators downwardly, and then pass up through the channels G^2 to the upper ends of the inner regenerators E^3 , through which they flow downwardly through the system H^3 , J' , H^4 to the waste gas stack. The streams of hot gases flowing from the risers to a regenerator come together in the upper

part thereof so as to fill the free space above the checkerbricks with a hot gas cushion and to cause the gases flowing through the said regenerator to spread the film about substantially all of the checkerbricks contained therein. In this manner the hot gases pass directly from the heating flues to each regenerator at approximately the temperature prevalent in the lowermost heating flue, and give up substantially all of their transferable heat to the regenerators due to the long path through them and to the large amount of active heat-receiving surface therein. Moreover, as the mass of gas passes over the top of G^2 into the upper part of regenerator E^3 , it films out and makes an intimate thermal contact with the underside of the oven floor before passing through the checkerbrick of E^3 . The cold air, on the other hand, flowing from passageway H^2 through regenerators E^2 and E' does not chill the oven floor. Apparently the combined effect of the heat retained by the masonry surrounding the base of the oven and the insulating cushion of hot gas adjacent to the underside of the oven floor protects the latter thermally, so that a coking temperature is always maintained throughout and including the intermediate portions of the coking oven.

Upon reversal of the dampers or valves, air will pass to the upper ends of the heating flues C through H^3 , E^3 , G^2 , E^4 , F' , and F^2 , while the combustion gases will flow from the lower ends of the heating flues C to the waste gas stack through E' , G' , E^2 and H^2 , as indicated by the dotted arrows shown in Fig. 4.

The advantages of my invention are important, both from the structural point of view and in the operation of the oven. Owing to the omission of the sole flues generally employed heretofore, the construction is simplified, and its cost reduced. The space formerly occupied by the sole flues is utilized for the upper portion of the regenerators, and in actual practice it has been found that the bottom of the oven can in this way be maintained at the required temperature, notwithstanding the absence of sole flues. Sole flue construction requires special and expensive refractory materials and intricacy of construction, whereas in the present invention the lower part of the coke chamber structure may be constituted of less expensive material and is structurally very much simplified. Elimination of these flues also means a decrease in the height of the battery and in the total length of the flue system through which the combustion gases (and the air) travel, and a relative increase in that portion of the flue system which serves as the active heating portion. The increased heating efficiency thus obtained decreases the coking time and the fuel con-

sumption, thereby reducing the operating cost. The shortening of the flue system also decreases the total resistance to the gas flow and this reduced resistance requires a much smaller chimney to meet the draft requirements than is required according to present coke oven practice, and in one instance, for example, I have found that I was able to obtain the proper draft with a chimney 25 feet lower than that which would have been necessary but for the incorporation in the coke oven of the principles of the present invention.

My invention enables me to employ an odd number of horizontal flue members, say one less than was usually employed hitherto (for instance five instead of six), which effects a decrease in the total length of the flue system and a relative increase in the active heating surface of the oven wall.

Although my invention has been illustrated in connection with a battery of ovens having independent heating flue systems in each wall of each oven, it is obvious that the invention is applicable to ovens having modified heating flue systems, such for example as ovens with cross-over passages connecting the uppermost of the heating flue passes either between adjacent coking chambers or over the top of each coking chamber. In such cases the direct connection between whatever type of horizontal heating flue system is used will be made with the proper regenerators at the appropriate terminals of the heating flue system, although in other respects the structure and operation of the ovens remains the same.

Various other modifications may be made without departing from the nature of my invention as defined in the appended claims.

1. A by-product coke oven battery comprising a series of alternate horizontal coking chambers and heating walls therefor arranged side by side in a row, each of said walls comprising a flue system containing zigzag, series-connected, superposed, combustion flues extending horizontally, laterally, and at least from end to end of each coking chamber, regenerators located beneath the coking chambers, the said regenerators having ports therein connected by direct upwardly extending communicating connections with the extreme ends of said combustion flue systems at opposite ends of the coking chambers and passages extending longitudinally of the oven battery and transversely to said coking chambers and beneath the regenerators, the said passages communicably connecting with the lower portions of the regenerators and with a waste gas stack respectively.

2. A by-product coke oven battery comprising a series of alternate horizontal coking chambers and heating walls therefor arranged side by side in a row, each of the walls comprising a flue system containing

zigzag, series-connected, superposed combustion flues extending horizontally, laterally and at least from end to end of the coking chambers, regenerators located at the lower portion of each of the coking chambers and having ports therein connected by direct communicating connections of a vertical character with the extreme ends of the flue systems at opposite ends of the coking chambers, passages extending longitudinally of the battery and beneath the regenerators, the said passages communicably connecting respectively with the lower portions of the regenerators and with a waste gas stack, and valves controlling said last named passages to periodically alter the direction of flow of the entering air and the exit products of combustion through the flues and regenerators.

3. A by-product coke oven battery comprising a series of alternate horizontal coking chambers and heating walls therefor arranged side by side in a row, each of the heating walls comprising a flue system containing zigzag, series-connected, superposed combustion flues extending horizontally laterally and at least from end to end of each of the coking chambers, regenerators located beneath the coking chambers, outer portions of the regenerators being located at the outer portions of the chambers and having ports at the opposite ends of the chambers in direct communicating connection with the extreme ends of the combustion flue systems, inner portions of said regenerators being located beneath the chambers and communicably connected with the outer regenerator portions at the lower parts thereof, passages located below the regenerators and communicably connecting with the inner portions of said regenerators and having provision respectively for the admission of air to said inner regenerator portions and for conveying combustion gases from said inner regenerator portions to a waste gas stack.

4. A by-product coke oven battery comprising a series of alternate horizontal coking chambers and having walls therefor arranged side by side in a row, each of said heating walls comprising a flue system containing zigzag, series-connected, superposed combustion flues extending horizontally, laterally and at least from end to end of each of the coking chambers, regenerators located immediately beneath the floor of each coking chamber and having a gas space at the upper part of each regenerator in direct heat-exchange relation with the underside of the coking chamber floor located thereabove, direct connections of a vertical character between and communicating with each regenerator and at least one of the terminal flues of each of two of the flue systems, each of said direct connections being so located as to enter the regenerator near the top thereof

at a level lower than the uppermost part of said gas space.

5. A by-product coke oven battery comprising a series of alternate horizontal coking chambers and heating walls therefor arranged side by side in a row, each of said heating walls comprising a flue system containing zigzag, series-connected, superposed, combustion flues extending horizontally, laterally, and at least from end to end of each of the coking chambers, regenerators located immediately beneath the floor of each coking chamber and having a gas space at the upper part of each regenerator in direct heat-exchange relation with the underside of the coking chamber floor located thereabove, direct substantially vertically extending communicating connections between each regenerator and at least one of the terminal flues of each of two of the flue systems, and two staggered spaced baffles for dividing each regenerator transversely of the coking chamber above it into a plurality of sections, the baffles being constituted of walls, one of which, nearer to the communicating connection between the regenerators and the flue systems, being closed at the top and open at the bottom, while the other is open at the top and closed at the bottom, whereby a sinuous gas passage is established between the sections of the regenerator.

6. In a battery of by-product coke ovens, the combination of a series of alternate horizontally elongated coking chambers and heating walls therefor arranged side by side in a row, each of said heating walls comprising a flue system containing zigzag, series-connected, superposed combustion flues, two pairs of narrow, deep regenerator compartments beneath each coking chamber and in direct heat-exchange relation with the bottom of each coking chamber, substantially throughout its extent, each pair of said regenerator compartments comprising an outer and inner section and two staggered adjacent baffles between the sections, each baffle providing a wall for one of said sections, the two baffles of each pair being so arranged as to provide a sinuous passage between the adjacent sections and a passage leading at each side of each outer regenerator section, near the top thereof, from and into the flue systems on each side of one of the coking chambers.

7. In a battery of by-product coke ovens the combination comprising a series of alternate horizontal coking chambers and heating walls therefor arranged laterally of each other in a row, a charge-supporting floor for each coking chamber, a flue system located within each side of each wall laterally of each coking chamber constituted of a series of horizontal, superposed, zigzag, series-connected flues, each extending the full length of the heating walls, the lowest hori-

zontal flue of the whole of said flue system lying laterally of the oven chambers, regenerator compartments extending between adjacent walls underneath the charge-supporting floor of the coking chambers from one end to the other end thereof, the upper part of each regenerator compartment defining an open unobstructed gas space bounded above by the lower surface of the oven floor, below by the upper surface of the regenerator checkerbrick and laterally by the side walls of the regenerator compartment, said gas space being adapted for substantial flow of heat into the coking chamber thereabove through the floor thereof, and communicating connections for establishing a direct flow between the terminals of the horizontal flue systems and ends of the open gas spaces contiguous to the ends of the coking chambers.

8. The by-product coke oven as set forth in claim 7, in which the connections last mentioned in the said claim are respectively adapted to feed heated air into or to withdraw products of combustion from the terminal flues of two of the heating systems into or from the regenerator compartments.

9. In a battery of by-product coke ovens, the combination comprising a series of alternate coking chambers and heating walls therefor arranged laterally of each other in a row, a charge-supporting floor for each coking chamber, each heating wall comprising a flue system containing horizontal, superposed, zigzag, combustion flues extending horizontally the full length of the chamber walls, the lowest horizontal flue of the flue systems lying laterally of the coking chambers, regenerators extending underneath the floor of the coking chamber from one end to the other end thereof, the upper part of each regenerator defining an unobstructed gas space bounded above by the lower surface of the oven floor, below by the upper surface of the regenerator checkerbrick, and laterally by the walls of the regenerator, said gas space being adapted for substantial flow of heat into the coking chamber thereabove through the floor thereof, and substantially vertical communicating connections for establishing a direct gas flow between the terminals of the horizontal flue systems and ends of the open gas spaces contiguous to the ends of the coking chambers.

10. The by-product coke oven construction as set forth in claim 9, in which one of the connections last mentioned in the said claim is in the form of a substantially vertical riser connecting a regenerator with the uppermost flue of a heating flue system, said riser being situated between two of the heating flue systems of adjacent coking chambers.

11. A coke oven of the character set forth

in claim 9 in which each of the heating flue systems consists of an odd number of horizontal combustion flues and vertical ducts communicably connecting the same and in 5 which the uppermost and lowermost members of the flue systems are communicably connected with the open gas spaces of the regenerators by substantially vertical ducts.

12. A coke oven of the character set forth 10 in claim 9 in which the heating flue systems include five horizontal combustion flues.

13. A by-product coke oven battery comprising a series of alternate horizontal coking chambers and heating walls therefor, 15 arranged laterally of each other in a row, each of said heating walls comprising a flue system on opposite sides thereof containing zigzag, series-connected, superposed combustion flues extending horizontally of 20 and at least from one end to the other end of each of the coking chambers, regenerators located immediately beneath the floor of each coking chamber and having a gas space at the upper part of each regenerator in 25 direct heat-exchange relation with the underside of the coking chamber floor located thereabove, baffles in each regenerator section, and a substantially vertical duct communicating connecting each of those sections 30 nearest to the sides of the battery, and one of the terminal combustion flues of each of two of the flue systems, said duct being so located as to enter the section near the top thereof at a level lower than the uppermost 35 part of the upper gas space in the regenerator section, passages extending longitudinally of the oven block and beneath the regenerators, the said passages connecting respectively with the lower portions of the 40 regenerators and with a waste gas stack, and valves controlling said last named passages to periodically alter the direction of flow of the entering air and the exit products of combustion through the flues and regenerators. 45

14. In a battery of by-product coke ovens comprising a series of alternate horizontal coking chambers and heating walls therefor arranged laterally of each other in a row, 50 each of said heating walls comprising a flue system containing zigzag, series-connected, superposed, combustion flues extending horizontally from end to end of the coking chamber, regenerator chambers immediately beneath each of the coking chambers communicably connected to the flue systems, and means for reversing gas flow through the respective regenerator chambers and heating flue systems, that improvement which comprises an upwardly extending passage for leading air from some of the regenerator chambers directly into the air inlet ports of the flue systems, and an upwardly extending passage for leading the products of com-

bustion from the flue systems directly into the other regenerators.

15. In a battery of by-product coke ovens, the combination comprising a series of alternate horizontal coking chambers and heating walls therefor arranged laterally of each other in a row, a charge-supporting floor for each coking chamber, a flue system located within each side of each wall laterally of each coking chamber, constituted of a series of horizontal, superposed, zigzag, series-connected, combustion flues, each extending substantially the full length of the heating walls, regenerators positioned immediately underneath the charge-supporting floor of the coking chambers from one end to the other end thereof, and direct upwardly extending communicating connections between the regenerators and the terminal horizontal flues of the flue systems. 75
